UNITED STATES PATENT OFFICE.

MURDOCH EVERETT SUTHERLAND, OF WESTVILLE, NOVA SCOTIA, CANADA.

RIFLE-SIGHT.

No. 888,858.

Specification of Letters Patent.

Patented May 26, 1908.

Application filed March 13, 1907. Serial No. 362,222.

To all whom it may concern:

Be it known that I, MURDOCH EVERETT SUTHERLAND, of Westville, in Pictou county, Province of Nova Scotia, Canada, have invented certain new and useful Improvements in Rifle-Sights, of which the following is a specification.

This invention relates to improvements to rifle sights and particularly to leaf sights of the type in which a laterally and longitudinally adjustable sight operates on a leaf hinged to a base which is secured to the rifle barrel.

The objects of my invention are, first, to provide an auxiliary emergency sight adjustable longitudinally but not laterally, whereby it remains always in its central position ready for instant action; second, to provide a peep sight adjustable with the open sight and which may be moved into the same sighting position as the open sight without in any way altering the adjustment thereof; the top of the peep sight being adapted in one position to serve as a bar sight; third, to provide a device whereby the adjustment of the elevating screw of the sighting bar may be indicated to the operator; and fourth, to provide means for gaging the alinement of the back sight with the foresight when the peep sight is used. The first of these objects is carried out by an auxiliary fixed sight integral with the sighting bar and extending normally thereto. The second by a plate slidably supported in a groove in the adjustable sight and having a peep hole therein and which may be moved into sighting position without disturbing the adjustment of the open sight. The third object is accomplished by a spring detent device operating on the elevating screw. And the fourth by forming the peep sight plate of such width as to the blanket sight and prevent its passing to the eye of the marksman when aiming. As a result, the marksman observes the foresight only through the peep-hole. The details of these constructions together with those of the remaining part of the sight are fully set forth and described in the accompanying specifications and drawings.

Figure 1 is a front elevation of the sight with the leaf in raised position. Fig. 2 is the same view with the leaf lowered. Fig. 3 is a side elevation with the leaf lowered. Fig. 4 is a perspective view of the sight in position on the rifle barrel. Fig. 5 is an enlarged perspective detail of the sighting bar

and laterally adjustable sights thereon. Fig. 6 shows a plan and elevation of the sighting plate with the open sight formed therein. Fig. 7 shows a plan and elevation of the peep sight plate. Fig. 8 shows a sectional detail along the line 2—2 in Fig. 6 when the peep sight plate is in position. Fig. 9 is a sectional detail along the line 3—3 Fig. 6 when the peep sight plate is in position. Fig. 10 is a central transverse sectional detail through the sighting bar and sighting plate. Fig. 11 shows an enlarged sectional detail of the top of the elevating screw. Fig. 12 is a section through the hood of the foresight. Fig. 13 shows a sectional detail of the lower end of the elevating screw.

In the drawings like letters of reference indicate corresponding parts in the figures.

Referring to the drawing, A is the base of any improved form which is suitably secured to the rifle barrel B.

C is the leaf hinged at a to the base and on which operates the sighting bar D, being raised and lowered thereon by means of the elevating screw E. The means connecting the elevating screw with the sighting bar do not form part of the present invention and may be varied to agree with different forms of sights, that I have illustrated being a form invented by me and covered by my United States Patent No. 824,960, which was granted to me on July 3rd, 1906.

F is the sighting plate of the type shown and described in my aforesaid United States patent and which is laterally adjustable on the sighting bar by means of the tangent screw G, and has an open V-shaped sight b on the top thereof. In accordance with my invention, plate F is formed with a dovetailed groove c on one side thereof, in which fits the peep sight plate H, having a peep hole d therein and an outwardly protruding thumb flange e, by means of which it may be raised and lowered. The peep sight plate is limited in vertical movement by means of a projecting pin f thereon which takes into a slot g formed in the bottom of the groove c. In its uppermost position the peep hole will come on a line with the top of the sighting plate F, and will thus be in the same sighting position as that of the open sight which it covers. To hold the peep sight plate in sighting position and to steady its movement, I provide a small compression spring h, located in a recess i in the plate and adapted to bear on the bottom of the groove c, and

take into a recess *j* therein when the peep sight plate is in its uppermost and sighting position. If it is desired to use the sight as a bar sight the peep sight is simply moved up 5 until the top thereof is on a line with the top of the sighting plate, provision being made for its retention in this position by means of the recess *x* in the bottom of the groove and in which the spring *h* takes.

10 I is the emergency sight plate, having an open V-shaped sight *k* cut therein, and which is formed integral with the sighting bar D, thus being adjustable longitudinally therewith on the leaf C, but being fixed from 15 lateral movement. The adjustment of the emergency sight for the different ranges is accomplished by means of ramps *s* and *t* formed integral with the base and which engage the underside of the sighting bar D.

20 The top *l* of the elevating screw E is in accordance with my invention engaged by a plunger *m* sliding in a recess *n* provided in a projecting portion *o* of the leaf. The plunger *m* is pressed outwardly by a compression 25 spring *p* and is adapted to successively engage a plurality of small depressions *q* which are symmetrically arranged around the underside of the head of the elevating screw. The screw E as it enters each depression will 30 cause a slight clicking noise thereby giving warning to the operator of the progress being made in the adjustment by means of the screw E. To take up the wear on the screw E and hold it firmly in position, I provide a 35 thimble *t* secured to the end thereof having a spring *u* therein which abuts one of supporting lugs *v* on the leaf, and so normally presses the elevating screw downwardly.

In constructing the sight plate H care is 40 taken that the width of the plate above the peep hole is such as to blanket the light passing through the hood of the foresight and prevent its passing to the eye of the marksman when aiming. As a result the marksman observes the foresight only when looking 45 through the peep hole and when looking above the edge of the peep sight plate would see nothing of the hood. For instance, if too coarse a sight should be taken the operator 50 would observe a line of light between the hood and the peep sight, but if the sight is properly taken then nothing can be seen through the peep sight but a clear, sharp circle, and looking over the top of the peep 55 sight plate nothing can be seen of the circle of the hood. By closely adjusting the width of the peep sight plate this gaging can be carried out to a great degree of fineness, and in addition to indicating whether the sight is 60 too coarse or too fine it will also serve as a check against rolling or canting the rifle, as in either of these cases a line of light will appear between the hood and the peep sight.

It will be observed that the emergency 65 sight is always ready for use in the center of

the rifle, and no matter what adjustment has been made on the regular sight to account for the windage, yet by lowering the leaf the emergency sight is instantly thrown into action and may be used from point blank range 70 up to 600 yards.

In using the peep sight adjustment can be made both vertically and laterally as on the open sight, and an important feature of the invention is that having adjusted the open 75 sight for a given range with the desired windage the peep sight can be then moved into the same sighting position as the open sight taking advantage of the adjustment previously made. The change from the open to 80 the peep sight is made by simply sliding up the peep sight plate into position.

While the invention has been herein described with great particularity of detail yet it will readily be understood that certain 85 changes may be made therein within the scope of the appended claims without departing from the spirit of the invention.

What I claim as my invention is:—

1. The combination with the sighting 90 plate having a dove-tailed groove therein having a smaller groove in the bottom thereof and a recess also in the bottom, of a peep sight plate having its edges of dove-tailed shape and slideable in the groove, a 95 pin on the plate entering the smaller groove and a spring adapted to take into the recess when the peep sight plate is in sighting position.

2. In a rifle sight the combination with the 100 leaf and sighting bar longitudinally movable thereon of an elevating screw for the sighting bar located at one side of the leaf, and having the head thereof protruding over the top of the leaf, a projection on the top of 105 the leaf having a recess therein, a plunger sliding in the said recess, and a spring normally pressing the same outwardly against the head of the elevating screw.

3. In a rifle sight the combination with 110 the sighting plate having an open sight therein of a peep sight plate slidably mounted thereon, the top of said peep sight plate being adapted to serve in a certain position as a bar sight and means for retaining the 115 peep sight plate in either of the two positions where it serves as a peep sight or a bar sight.

4. In a rifle sight the combination with 120 the leaf, the sighting bar slideable thereon, the elevating screw for the sighting bar and the supporting means therefor of a thimble secured to the end of the elevating screw, and a spring therein adapted to abut the supporting means of the elevating screw. 125

5. In a rifle sight, the combination with a circular hood, of a peep sight plate having a peep hole therein, the peep sight plate above the peep hole being of such width as to blanket the light passing through the 130

hood of the foresight about the foresight and prevent its passing to the eye of the marksman when aiming, whereby the amount of foresight taken may be gaged, as and for 5 the purpose specified.

6. In a rifle sight, the combination with the leaf and sighting bar longitudinally movable thereon, of an elevating screw for the sighting bar located at one side of the 10 leaf and having the head thereof protruding over the top of the leaf, a projection on the top of the leaf having a recess therein and a detent device in said recess operating on the head of the elevating screw, as and for 15 the purpose specified.

7. In a rifle sight, the combination with the adjustable sighting plate having a groove formed therein, of a peep sight slidable in said groove and in its innermost position 20 adapted to remain out of sighting position, and a spring adapted to be thrown into operation by the outward sliding of the peep sight and adapted to hold the same in sighting position, as and for the purpose specified.

25 8. In a rifle sight, the combination with the adjustable grooved sighting plate having

a sight formed at one edge thereof and a small groove at the bottom thereof, of a peep sight slidable on the sighting plate, having a peep hole therein adapted to register with the sight when the peep sight plate is in its outermost position, and a pin on 30 the peep sight plate extending in the small groove.

9. In a rifle sight, the combination with the adjustable grooved sighting plate having a sight formed at one edge of the same and a recess formed in the bottom of the grooved portion, of a peep sight plate slidable in the 35 sighting plate having a peep hole therein 40 adapted to register with the sight on the sighting plate when the peep sight plate is in its outermost position, and a spring on the peep sight plate adapted to take into the recess when the peep sight plate is in its 45 outermost position.

Signed at Ottawa, in the Province of Ontario, this 6th day of March, 1907.

MURDOCH EVETT SUTHERLAND.
